UNITED STATES PATENT OFFICE.

ROBERT EDWARD EWING, OF PITTSBURGH, PENNSYLVANIA, ASSIGNOR TO PITTSBURGH LAMP, BRASS & GLASS COMPANY, OF PITTSBURGH, PENNSYLVANIA, A CORPORATION OF NEW JERSEY.

DESIGN FOR A HANGER FOR LIGHT-REFLECTING BOWLS.

47,688.

Specification for Design.

Patented Aug. 10, 1915.

Application filed April 30, 1914. Serial No. 835,533. Term of patent 3½ years.

To all whom it may concern:

Be it known that I, ROBERT E. EWING, a citizen of the United States, residing at Pittsburgh, in the county of Allegheny and State of Pennsylvania, have invented a new, original, and ornamental Design for Hangers for Light-Reflecting Bowls, of which the following is a specification, reference being had to the accompanying drawing, forming part thereof.

Figure 1 is a front view of a hanger for light reflecting bowls showing my new design; and Fig. 2 is a side view of the same.

I claim:

The ornamental design for a hanger for light reflecting bowls as shown.

ROBERT EDWARD EWING.
